DESIGN FOR AN EXPANSIBLE LINK CHAIN FOR A BRACELET OR THE LIKE

Joseph M. Bender, Manhasset, N. Y., assignor to
Jacohy-Bender, Inc., New York, N. Y., a corporation of New York

Application March 2, 1949, Serial No. 1,170

Term of patent 7 years

(CL. D45—4)

To all whom it may concern:

Be it known that I, Joseph M. Bender, a citizen of the United States and a resident of Manhasset, county of Nassau, and State of New York, have invented a new, original, and ornamental Design for an Expansible Link Chain for a Bracelet or the like, of which the following is a specification, reference being had to the accompanying drawing, forming a part thereof, in which:

Fig. 1 is a top plan view of an expansible link chain in contracted condition, showing my new design;

Fig. 2 is a side elevational view of the chain of Fig. 1, the conventional bottom links being shown in broken lines;

Fig. 3 is a top plan view of the expansible link chain in an expanded condition, portions of the conventional bottom links being visible between the top links;

Fig. 4 is an edge elevational view, on a larger scale, of one of the top links taken from the right of Fig. 1; and

Fig. 5 is a similar edge elevational view taken from the left of Fig. 1.

I claim:

The ornamental design for an expansible link chain for a bracelet or the like, as shown.

JOSEPH M. BENDER.
